(57) **CLAIM**

The ornamental design for a tractor head lamp, as shown and described.

DESCRIPTION

FIG. 1 is a left perspective view of the tractor head lamp showing our new design;

FIG. 2 is a top view thereof;

FIG. 3 is a bottom view thereof;

FIG. 4 is a front view thereof;

FIG. 5 is a rear view thereof; and,

FIG. 6 is a left side view thereof.

The broken line showing of the tractor head lamp is included for the purpose of illustrating environmental structure and forms no part of the claimed design.
